UNITED STATES PATENT OFFICE.

HENRY P. COMPTON, OF GEORGETOWN, TEXAS, ASSIGNOR TO EASY RIDER KNEE PAD CO., OF GEORGETOWN, TEXAS.

KNEE PAD.

Application filed November 4, 1921. Serial No. 512,860.

To all whom it may concern:

Be it known that I, HENRY P. COMPTON, citizen of the United States, residing at Georgetown, in the county of Williamson and State of Texas, have invented certain new and useful Improvements in Knee Pads, of which the following is a specification.

This invention relates to an improved 10 knee pad particularly designed for use by those who are required to work in a kneeling position and has as its salient object to provide a pad which will form an effective protection for the knee.

15 A further object of the invention is to provide a pad which may be cheaply constructed and which will embody a knee cushion.

And the invention has as a still further object to provide a pad wherein the filling of the cushion may be readily renewed but wherein the filling will, under ordinary conditions, be retained in a cushion sack employed.

25 Other and incidental objects will appear hereinafter.

In the drawing:

Figure 1 is a perspective view of my improved knee pad,

29 Figure 2 is a longitudinal sectional view taken medially through the device, and

Figure 3 is a plan view showing the blank from which the shoe of the pad is formed.

In carrying the invention into effect, I 35 employ a shoe 10. This shoe is preferably formed of laminated fabric adhesively connected by a rubber binder vulcanized so as to not only effectually secure the laminations together but to also render the shoe 40 water-proof. I have found, incident to the actual manufacture of the invention, that worn out tire casings may be employed in constructing the shoe. A useful purpose for such casings is thus provided while, at the 45 same time, such casings, even though too badly worn to be of further service in their original capacity, are, nevertheless, sufficiently intact to provide excellent stock from which to construct the shoe of the 50 present invention. As shown in Figure 3, the shoe is preferably constructed from an oblong blank having parallel side and end edges and comprising a body A at one end of which is an end flap B, alined trans- 55 versely directed slits C being formed in the

blank from the longitudinal edges thereof to define the end flap. To fashion the shoe, the side margins of the body A of the blank are first bent upwardly to define upstanding side walls 11 when the flap B of the 60

blank is then directed upwardly and folded rearwardly over the forward ends of the side walls at the outer faces thereof to form a front wall 12 for the shoe, it being ob- 65 served in this connection, that the front wall 65

extends somewhat above the side walls. Securing the front wall at its ends to the forward ends of the side walls are pairs of rivets or other approved fastening devices, 70

the rivets of each pair, for convenience, being indicated at 13 and 14 respectively, and, if desired, the joints between these walls may be vulcanized so as to render the shoe 75

water-tight. Riveted at one end to one of the side walls of the shoe, near the rear end 75

of said wall, is an attaching strap 15. A similar strap 16 is secured at one end to the shoe at its adjacent side by one of the rivets 14. Upon the opposite side wall of the shoe is secured a buckle 17 to engage 80

the strap 15 while a similar buckle 18 is provided to engage the strap 16, the short strap carrying the buckle 18 being secured by the other of the rivets 14 at the adjacent 85 side of the shoe. The straps 15 and 16 are, of course, provided for securing the shoe to a leg of the wearer.

Arranged within the shoe is a knee cushion. This knee cushion comprises a sack 90 which is preferably formed of canvas and snugly fits within the shoe. The open inner end of the sack is, as best shown in Figure 2, disposed to confront the end wall 12 of the shoe and securing the upper margin of the sack at its mouth to said wall are 95 one or more lines of stitching 20. The lower margin of the sack at the mouth thereof is cut away, as shown at 21, and held within the sack is a stuffing 22. This stuffing is preferably of sponge rubber but may be of cotton, waste, cork, hair or other approved material and, as will be observed, when the sack is in its normal position within the shoe, the mouth of the sack will be closed by the end wall 12 of the shoe to 100 prevent accidental loss of the stuffing. However, by swinging the outer end of the sack upwardly over the end wall 12, as shown in dotted lines in Figure 2, the mouth 105 of the sack will be rendered accessible so 110

that the stuffing may be readily removed and renewed, the sack in being cut away at its mouth, as indicated, making it entirely convenient to withdraw the stuffing from

5 the sack. In practice, the knee of the user of the device will rest upon the cushion so that the device will accordingly provide an entirely comfortable and effective pad.

Having thus described the invention, what 10 is claimed as new is:

1. A knee pad including a shoe, and a cushion containing sack arranged within and resting on the bottom of the shoe having its mouth open and normally covered by 15 a wall of the shoe.

2. A knee pad including a shoe, and a

cushion containing sack secured at its mouth to a wall of the shoe and normally resting on the bottom of the shoe with its mouth covered by said wall.

3. A knee pad including a shoe having side and end walls, a cushion containing sack lying within the shoe and having its upper margin at the mouth thereof secured to said end wall, the mouth being normally covered by the end wall and the sack being free of the shoe except at the upper margin of its mouth, and a stuffing within the sack.

In testimony whereof I affix my signature.

HENRY P. COMPTON. [L.S.]
